(57) CLAIM

I claim the ornamental design for a golf club head, as shown and described.

DESCRIPTION

FIG. 1 is a front perspective view showing the golf club head of my design;

FIG. 2 is a front view thereof;

FIG. 3 is a rear view thereof;

FIG. 4 is a top view thereof;

FIG. 5 is a bottom view thereof;

FIG. 6 is a view looking from the toe of the club head; and,

FIG. 7 is a view looking from the heel of the golf club head.

The broken line showing is for illustrative purposes only and forms no part of the claimed design.
